UNITED STATES PATENT OFFICE.

FRANK C. PERKINS, OF CHICAGO, ILLINOIS, ASSIGNOR TO THE CHICAGO
RAZOR STROP COMPANY, OF SAME PLACE.

BICYCLE TOOL-BAG.

SPECIFICATION forming part of Letters Patent No. 590,936, dated September 28, 1897.

Application filed August 23, 1895. Serial No. 560,199. (No model.)

To all whom it may concern:

Be it known that I, FRANK C. PERKINS, a citizen of the United States, residing at Chicago, in the county of Cook and State of Illinois, have invented a certain new and useful Improvement in Bicycle Tool-Bags, which is fully set forth in the following specification, reference being had to the accompanying drawings, in which—

10 Figure 1 is a side elevation of my tool-bag attached to a bicycle and closed. Fig. 2 is a vertical section of the bag unattached and open. Figs. 3 and 4 are plans of the leather blanks from which the two shells of my tool-bag are constructed.

15 The object of my invention is to make a bicycle tool-bag which can be attached in the most convenient and least conspicuous part of the bicycle, which is easily opened and closed, and is both simple and economical in manufacture.

20 It is a further object of my invention to provide a tool-bag wherein the sections comprising the same have a telescopic connection 25 one with the other, so as to adapt themselves to accommodate more or less tools and of being able to tightly clamp such tools therein by drawing the sections close together, thus preventing rattling of such tools or other articles placed within the bag.

30 My tool-bag is made in two shells, an inner A and an outer B, each built up from a blank, usually of leather, that for the inner shell being shown in Fig. 3 and that for the outer in Fig. 4. The inner blank consists of a back M, with two end flaps m and m', a lateral flap M', with two end flaps m² and m³, and a second lateral flap M², with end flaps m⁴ and m⁵. The blank for the outer shell is similar in

40 form. The part N is pierced with the slits pp' and the end flaps n³ and n⁵ with the slits q and q', respectively. To construct the tool-bags from these blanks, the flaps M' and M² are bent up to right angles with M. m² and 45 m⁴ are then bent together at right angles with M' and M², respectively, so that the one end flap is partially superimposed upon the other and are retained in this position by a rivet H³.

50 The end flap m' is now bent up to approximately a right angle with M' and the end

flaps m³ and m⁵ are bent together at right angles with M' and M², respectively, so as to be partially superimposed upon each other and upon M', where they are held by rivets H, H', and H². The flaps of the blank for the outer shell N', N², n', n³, and n⁵ are similarly bent and riveted together. The end flaps n² and n⁴ are then bent together at right angles with N' and N², after which n is bent up, and the three are held together by one or more 60 rivets I³. The said rivets I³ also pass through the end flap n of the inner shell, as shown in Fig. 2. Thus the inner shell is hinged to the outer at the point X. To prevent the shells from opening too far, their upper portions are 65 secured to each other by the strap T, attached to the inner shell by the rivet H and to the outer by the rivet T'. To retain the shell A within the shell B when the tool-bag is closed, a strap-and-buckle device R is used, consisting of a strap R' (shown in Fig. 1) and a buckle R², (shown in Fig. 2,) attached to opposite sides of the outer shell. To facilitate opening the bag, a button S may be attached to the back of the inner shell. 70

75 My tool-bag is designed to fit in that angle of the framework of a bicycle made by the horizontal brace C and the more or less upright brace D. The bag will thus be partially 80 under the seat F and will be almost wholly concealed by the person of the rider. To retain the bag in this position, the two strap-and-buckle attachments P and Q may be used, consisting, respectively, of buckles P' and Q' and straps P² and Q², the said straps being 85 passed, respectively, through the slits pp' and q q' and buckled about the frame elements D and C, as shown in Fig. 1.

In cutting the blank for the outer shell the shape of the flaps N' and N² will be determined by what is the usual angle between C and D of the frame. The blank for the inner shell will be so cut that from the pivot-point X the lines X Y and X Z shall be equal to each other and approximately to the line X V. 90

95 It is thus apparent that my tool-bag is economical in construction, dispensing with all sewing, and requiring no skilled and but little manual labor; it opens readily, assisted therein by the action of gravity, and remains 100

open while yet retaining perfectly its contents; it may be made of any size, and in any given size its capacity may be decreased or increased by strapping the two shells more 5 or less closely together upon the principle of the traveling-telescope.

In the construction of tool-bag herein shown and described it will be noted that the sections comprising the same are of substantially equal dimensions, each diminishing in depth toward the bottom, and one telescoped within the other. The object of this construction is twofold: First, the shells being practically wedge-shaped, the tools placed in the bag will fall to the bottom and be wedged therein, and, secondly, owing to the telescopic connection of the two shells, they can be tightly drawn together to firmly hold the tools and prevent all liability of rattling.

20 What I claim as my invention, and desire to secure by Letters Patent, is—

1. A bicycle tool-bag consisting of two shells of substantially equal dimensions, diminishing in depth toward their lower ends, 25 and each having an open inner side, one of said shells being hinged at its lower end to the lower open portion of the adjacent shell, so as to have a telescopic connection therewith, and means for attaching one of said 30 shells to the frame of a bicycle, substantially as described.

2. A bicycle tool-bag consisting of two shells of substantially equal depth, and each having an open inner side, one of said shells 35 being provided at its lower portion with a flap made integral with its body, said flap being secured within the bottom portion of one of said shells and serving as a hinge connection between the two shells, the parts being 40 so arranged that one telescopes within the other, a strap secured within the two shells to limit their outward opening movement, and means for attaching one of the shells to

the frame of a bicycle, substantially as described.

3. A bicycle tool-bag consisting of two shells, each shell constructed from a single blank, comprising a back portion, M; side flaps, M' and M²; and end flaps, m, m', m², m³, m⁴ and m⁵; the flap, m serving as a hinge by 50 which the inner shell is hinged, at its lower end, within the outer shell, and adapted to swing downward and outward to open said tool-bag.

4. A bicycle tool-bag consisting of two independent shells of substantially equal dimensions and diminishing in depth toward the bottom and each having an open inner side, one of said shells being provided at its bottom with a flap made integral with its 60 body, said flap being secured to the bottom portion of the adjacent shell and serving as a hinge connection between the two shells, the parts being so arranged that one telescopes within the other and the open side of 65 the movable shell closing toward the rear wall of the stationary shell, substantially as described.

5. A bicycle tool-bag consisting of two counterpart shells of substantially equal dimensions and diminishing in depth toward the bottom and each having an open inner side, means for attaching one of said shells to the frame of a bicycle, the other shell being hinged at its lower end to the lower open 70 portion of the stationary shell so as to have a telescoping connection therewith, the open inner side of the movable shell closing toward the rear wall of the stationary shell, and means for limiting the swinging open of 75 the said movable shell, substantially as described.
